UNITED STATES PATENT OFFICE.

GEORGE F. BASON, OF ITHACA, NEW YORK.

AMPERE-HOUR METER.

Application filed November 28, 1923. Serial No. 677,563.

My invention relates to electrical measuring instruments and particularly to ampere-hour meters for alternating-current circuits.

One object of my invention is to provide a meter or motor device comprising a rotary element and current-responsive means tending to cause the element to rotate in direct proportion to the amperes of an alternating-current circuit.

Another object of my invention is to provide a device of the above indicated character that shall be simple and durable in construction, economical to manufacture and effective in its operation.

A further object of my invention is to provide an alternating-current ampere-hour meter that shall have a substantially straight-line operation characteristic.

In practicing my invention, I provide a meter, similar to an ordinary induction motor meter, that is provided with a rotatable armature and actuating field magnet coils for energization in accordance with the current of an alternating-current circuit.

A flux shifting or closed-circuit element is so mounted to turn or float in the air gap between the armature and its field magnet, against the action of a spring, as to cause the armature to rotate in substantially direct proportion to the current of a circuit to be measured.

Figure 1 of the accompanying drawings is a front elevational view of an instrument embodying my invention, a portion of the armature thereof being broken away, and

Fig. 2 is a detail view taken along the line II-II of Fig. 1.

The instrument 1 comprises a supporting base structure 2, a bracket 3 mounted on the base structure 2, a laminated magnetizable core member 4 secured to the bracket 3, as by screws 5, and field magnet coils 6 mounted on the pole ends 7 of the magnetizable core member 4. A shaft 8, having a worm-screw portion 9, for driving an integrating mechanism (not shown) is supported at its upper and lower ends by bearings 11 and 12 supported on the bracket 3 and the base member 2, respectively.

A damping disc 14 is mounted on the shaft 8, adjacent to the lower end of the latter and is adapted for co-operation with a permanent magnet 15 that may be secured to the base structure 2, as by a screw 16.

An armature 18, of aluminum or other suitable material, is of substantially inverted

cup shape having an upper collar or flange 19 by which it may be rigidly secured, as by a screw 20, to the shaft 8 with its vertical sides adapted to rotate between the pole ends 7 of the core member 4.

A laminated member 22 is rigidly secured in position concentric with the armature 18 to conduct the flux from one pole end to the other, through the armature 18. The shaft 8 passes freely through the member 22.

A flux-shifting member 23, preferably of copper strap or sheet material, is constructed in the form of a rectangle having portions 24 opposite the pole ends 7 and openings 25, 70 therein to form a close-circuited conducting turn around one side of the pole face.

The member 23 is adjustably clamped, as by nuts 27, to a screw-bearing shaft 28 having its hollow lower end 29 mounted to pivot 75 around the upper end of a pin projection 30 on the bearing member 11.

A helical spring 32 is secured, at its inner end, to the shaft 28, and, at its outer end to a member 33 that is mounted, as by screws 80 34, to the pin projection 30.

In operation, when the coils 6 are energized in accordance with the alternating current of a circuit to be measured, the armature 18, by the interaction of the current induced in the portion 24 of the member 23, with the magnetic field and with the current induced in the armature, is caused to rotate. The driving torque producing this rotation of the armature would, for a given 90 fixed position of the member 23, be proportional to the square of the current being measured; but, with increase of current in the coils 6, the portions, or shading coils 24, 95 tend to move out of the magnetic field, as indicated by dotted lines in Fig. 2, and are brought to rest by the action of the spring 32 in a new position where they produce less shading of the field. Thus, the driving torque on the armature will always be less than proportional to the square of the current being measured.

By the proper choice of the zero position of the portions 24 and the proper adjustment of the spring 32, the driving torque on the armature 18 may be made directly proportional to the current in the coils 6. With the usual permanent magnetic braking, as effected by the magnet 15 on the disc 14, the speed of rotation of the armature 18 thus 105 becomes substantially proportional to the current in the coils 6.

22

While I have shown and described a particular form of my invention, changes may be effected therein without departing from the spirit and scope thereof, as set forth in the appended claims.

I claim as my invention:

1. An alternating-current integrating meter comprising a rotatable armature having a fixed axis of rotation, a series coil for producing the actuating flux therefor and a movable flux-affecting member for causing the same to be actuated substantially in direct proportion to the current of a circuit.
2. An alternating-current integrating meter comprising a rotatable member controlled by magnetic flux and having a fixed axis of rotation and movable means for varying the magnetic flux to cause the member to rotate substantially in direct proportion to the current of a circuit.
3. An alternating-current integrating meter comprising a rotatable member having a fixed axis of rotation and means for rotating the same including movable means tending to cause the member to rotate substantially in direct proportion to the current of a circuit.
4. An alternating-current integrating meter comprising a rotatable armature having a fixed axis of rotation and electrically-controlled means including a movable flux-affecting member for actuating the same substantially in direct proportion to the current of a circuit.
5. An alternating-current integrating meter comprising a flux-responsive movable member and flux-shifting means including a

member movable independently of said first movable member for actuating the same substantially in direct proportion to the current of a circuit.

6. An alternating-current-circuit integrating meter comprising a rotatable armature having a fixed axis of rotation, a coil energized from said circuit for producing actuating flux for the armature and means, including a movable flux-affecting member, for causing the armature to be actuated substantially in direct proportion to the current in said coil.

7. An alternating-current ampere-hour meter comprising a rotatable armature having a fixed axis of rotation, a field magnet therefor, a spring, a flux-shifting member mounted to float in the magnetic field between the armature and the magnet against the action of said spring and means for producing a breaking torque in direct proportion to the speed of the armature.

8. An alternating-current ampere-hour meter comprising a rotatable armature having a fixed axis of rotation, a field magnet therefor, a resilient member, a flux-shifting member mounted to turn in the magnetic field between the armature and the magnet against the action of the resilient member, and means for producing a braking torque in direct proportion to the speed of the armature.

In testimony whereof, I have hereunto subscribed my name this 22nd day of November 1923.

GEORGE F. BASON.
